COOKY CUTTER

Emily M. Fricke, Plattsmouth, Nebr.

Application August 6, 1954, Serial No. 31,753

Term of patent 7 years

(Cl. D44—8)

Fig. 1.

Fig. 2.

Fig. 3.

I claim:

The ornamental design for a cooky cutter, as shown.
